UNITED STATES PATENT OFFICE

2,183,272

RAIL JOINT SHIM

Fred S. Wonham, New York, N. Y., assignor to
The American Fork & Hoe Company, Cleve-
land, Ohio, a corporation of Ohio

Application August 2, 1938, Serial No. 222,657

1 Claim. (Cl. 238—244)

My invention relates to improvements in rail joint constructions, and relates more particularly to improvements in wear compensating shims therefor.

5 I am familiar with shims of the prior art wherein a one-piece or unitary shim is provided with means which provide additional resilient yielding thereof.

Many of these shims are provided with T-
10 slots and the like in a downwardly projecting
apron disposed between bolts projected through
the joint bars. Said apron is generally in the
form of a tab or extension of the central por-
tion of the shim disposed intermediate a pair
15 of adjacent rail bolts and traversing the inter-
mediate juncture of the rail ends.

I am further familiar with shims of the prior
art having a centrally disposed downwardly pro-
jecting apron centered between the rail bolts se-
20 curing the joint bars and rail heads together.
In many of these constructions a certain amount
of objectionable movement of the shim occurs.

In "half shims" the two halves sometimes
"creep" toward the juncture of the rail ends and
25 overlap.

It is an object of my invention to provide ad-
ditional strength in shims of this type and to
provide more positive location of such shims in
the joint.

30 Another object of my invention is to minimize
the tendency of shims to break or "buckle" in the
center portions.

Another object of my invention is to prevent
distortion or lateral movement of such shim in
35 the joint.

Other objects of my invention and the inven-
tion itself will become increasingly apparent
from a consideration of the following description
of the drawing wherein:

40 Fig. 1 is a cross-sectional view of a rail joint
with an embodiment of my invention therein;

Fig. 2 is a side elevational view of the joint
of Fig. 1 with a joint bar thereof removed for
clarity.

45 Referring now to the drawing in all of which
like parts are designated by like reference char-
acters, in Figs. 1 and 2, I have shown at 1 and 2
a pair of rails comprising each a head 3, a base
4 and a web 5; the two adjacent end portions of
50 the rails 1 and 2 being conventionally jointed to-
gether by a pair of joint bars 6—6 having in-
clined surfaces 7—7 adapted to be wedgingly en-
gagable with corresponding inclined surfaces
8—8 on the under side of the rail head 3 and
55 having inclined flanges 9—9 adapted to wedging-

ly engage the upper surfaces of the rail flange
4. The joint bars 6—6 are thrown into wedging
engagement with the rail head under surfaces
8—8 by bolts 10 projected through aligned per-
forations in the joint bar 6—6 and the rail web 5
5 and having nuts 11 on the bolts 10.

Shims 12—12 preferably made of sheet metal
are employed in the manner well known in the
art between the surfaces 7 and 8 to compensate
for wear therebetween and the shim 12, illus- 10
trated in the drawing herein in connection with
which my invention will now be explained, com-
prises a flange 13 disposed between the rail head
and the joint bar between the inclined surfaces 7
and 8 thereof to compensate for wear therebe- 15
tween, a flange formed body 14 supporting the
flange 13 and disposed between the joint bar 6—6
and the web 5. The said flange formed body 14
comprises in the form shown in Fig. 2 a portion
which is of length equal to or greater than the 20
length of the flange portion 13 and which is pro-
vided with arcuate notches at portions 15 there-
of to provide rail bolt receiving portions which
circumscribe the top and sides of said rail bolts
in a manner to positively locate the shims 25
against lateral movement of the rails. The outer
portions 16—16 of said flange body portion 14
strengthen or reinforce the shim 12 against
"buckling" of the intermediate or lug portion 17
which, in the form shown in Fig. 2, has an in- 30
verted T-slot formed therein.

It is to be understood that the lug 17 could
for the purpose of this invention be slotted or
notched in any preferred manner. Various forms
of such slots are shown in United States Letters 35
Patent No. 2,071,151, issued to me and are pro-
vided for the purposes described therein, briefly,
to allow resilient yielding of the shim. It is to
be further understood that my invention may be
applicable to shims of this general type which 40
are not notched or slotted in such central por-
tion.

In the present invention, I have added the por-
tion 16—16 which imparts an additional strength
to the shim and particularly to a shim weakened 45
by the removal of metal from its center portion,
as in Fig. 2. I have further provided by such
portion 16, double location of the shims in the
joints since each side 16 of the intermediate or
lug portion 17 encompasses the sides and top of 50
the rail bolts disposed laterally of the center or
intermediate portion of the shim.

It is to be understood that the tendency to-
wards any "buckling" of the center lug portion
17 because of the removal of metal from the lug 55

in order to increase its flexibility is eliminated by this construction. Further, that any distortion or lateral movement of the shim in the joint is definitely prevented hereby in the case of a 5 shim of the general type which is tapered from the center of juncture of the rail ends to the ends of the shim and in which type shim in prior constructions there is a marked tendency of the shim to creep along the taper plane towards the 10 center of the joint.

10 The removal of metal from the center lug portion 17 of the shim considerably reduces any tendency to crack in this zone due to the increased flexibility of the shim parts but if cracking 15 occurs to divide the shim in two parts, the parts are prevented from creeping towards each other and overlapping by the engagement of each part with its associated bolt 10 at the notch portion 15.

20 Obviously, shims of either symmetrical or stepped pattern may be employed.

I am aware that numerous and extensive departures may be made from the forms herein 25 illustrated and described without departing from the spirit of my invention.

I claim:

A unitary wear compensating shim for rail

joints, comprising a pair of longitudinally aligned 5 shim portions, each adapted to be placed between fishing surfaces of a rail joint bar and the bottom fishing surface of the head of a different one of the two rail end portions included in the 10 joint, each shim portion comprising an integral apron pendants extending between a rail web and the opposing relatively spaced inner surface of the joint bar, and a resiliently flexible relatively narrow strip or web formed integrally with 15 said shim portions extending between and interconnecting them at substantially the level of the joint bolts, said strip uniting said portions and being of substantial length and yieldable responsive to relative movements of the rail joint ends, 20 each said apron extending laterally beyond the adjacent rail joint bolt and having a notch extending from its bottom edge to closely encompass the upper and both side surfaces of said joint bolt, and preventing substantial dislodgment of the shim portion towards or away from the rail ends, whereby buckling or breaking of the strip is avoided and creeping of the shim portions longitudinally of the joint is substantially 25 prevented.

FRED S. WONHAM.
